UNITED STATES PATENT OFFICE.

GEORGE WILKINSON AND JAMES McCOURT, OF ACAMPO, CALIFORNIA.

EARTH-SCRAPER.

SPECIFICATION forming part of Letters Patent No. 380,374, dated April 3, 1888.

Application filed September 30, 1887. Serial No. 251,144. (No model.)

To all whom it may concern:

Be it known that we, GEORGE WILKINSON and JAMES McCOURT, citizens of the United States, residing at Acampo, in the county of 5 San Joaquin, State of California, have invented certain new and useful Improvements in Three-Wheel Platform-Scrapers, of which the following is a specification, reference being had therein to the accompanying drawings.

Our invention relates to certain improvements in that class of earth-scrapers used for grading and leveling off land and for ditching purposes; and it consists in the combination of certain parts, as hereinafter explained, and 15 pointed out in the claims.

Referring to the accompanying drawings, Figure 1 is a right-hand side elevation of our scraper, the dotted lines thereon representing the position of the lever, &c., and of the 20 scraper when elevated and in a position of discharge. Fig. 2 is a plan of the same.

The platform A is suitably mounted in front bearing-wheels, A', the rear of such platform being supported by a trail-wheel, A''. A 25 rod, G, is rigidly attached at a point near the front of the platform, and has forwardly-extending flexibly-attached adjustable arms F, to which are flexibly attached the scraper B, whose position and operation are controlled by 30 a system of levers composed of a bail, B', attached to the scraper, and having attached to it at its center a lever, D, whose fulcrum is a vertical forked post, d, attached at the front of the platform A to a center bar, a, to the 35 rear of which is attached a foot, b, to which is attached flexibly a notched vertical post, D², which engages with the rear of the lever D by means of a spring detent-handle, D'.

By means of the above-described leverage 40 devices the scraper B is raised and lowered vertically, and in connection with an auxiliary-lever device, which will now be described, controls the position and operation of the scraper B. This auxiliary-lever device consists of a vertical lever, E', attached to the 45 bar a forward of the post D², and connected by a bar, E, with the center of the rear edge of the scraper B. This bar E passes through the forks of the post d, such forks acting as 50 a guide thereto. The position of the lever E'

is controlled by a spring thereon engaging with the notches of a notched half-circle, E', attached to the bar a. The hounds of the pole C, to which the team is attached, are attached to the sides of the scraper A. The 55 distance of the scraper from the platform may also be regulated by changing the position of the straps F upon the rod G, there being perforations in such straps for that purpose.

To operate the scraper the same is vertically 60 adjusted by the lever D. The scraper's angle to the soil is regulated by the lever E'. When the load is secured, it may be discharged by raising it by means of the lever D; or the lever E' may be depressed rearwardly, raising 65 the edge of the scraper with its load, and the rear of the lever D, being depressed, raises the scraper and its load for transportation to any desired point.

Having thus described our invention, what 70 we claim as new is—

1. A mounted scraper composed of the platform A, suitably mounted on the wheels A' A'', and provided with the longitudinal bar a, the scraper B, provided with pole and hounds 75 C and bail B', and a suitable system of levers for controlling the operation and position of the scraper, all combined and operating as set forth.

2. The scraper B, attached to the front of 80 the platform A by means of the adjustable arms F, and its bail B', in combination with the levers D and E', suitably attached to the scraper, the fulcrum of the lever D' being a vertical forked standard, d, attached at its 85 foot to the bar a, attached longitudinally to the center of the platform A, all as herein described and set forth.

3. The combination, substantially as described, of the platform A, mounted on the 90 wheels A' at its front end, the trail-wheel A'' at its rear, the longitudinal bar a, the foot b, the forked post d, the arms F, the scraper B and its bail B', the tongue and hounds C, and suitable lever devices for controlling such 95 scraper from the platform A.

4. The platform A, suitably mounted, and having the scraper attachment B B' C attached at its front end by the adjustable arms F, attached to the cross-rod G, in combination 100

with such cross-rod and with the foot-piece *b*, having the vertical post *D*² attached thereto, such post engaging with the lever *D*, having its fulcrum at the apex of the forked post *d*, secured to the longitudinal bar *a*, secured to the platform *A*, the rod *E*, and the lever *D*, being suitably connected with the scraper *B*' all as shown and described.

In testimony whereof we affix our signatures in presence of two witnesses.

GEORGE WILKINSON.
JAS. McCOURT.
